United States Patent Office

Des. 195,817
Patented Aug. 6, 1963

195,817

SAFETY SHOE

Roger Tronche, Coutras, France, assignor to
Baudou S.A.R.L., Les Eglisottes, France

Filed Apr. 15, 1963, Ser. No. 74,446

Claims priority, application France Oct. 18, 1962

Term of patent 14 years

(Cl. D7—7)

FIGURE 1 is a side elevational view of a safety shoe showing my new design; the side opposite being the same except the lacing being omitted; and

FIGURE 2 is a perspective view thereof.

I claim:

The ornamental design for a safety shoe, as shown and described.
